LINE CASTING MACHINE

Ransom H. Turner, Auburndale, N. Y., assignor to
Intertype Corporation, Brooklyn, N. Y., a corporation of New York

Application May 20, 1933, Serial No. 672,055
In Germany June 1, 1932

11 Claims. (Cl. 199—50)

The present invention relates to improvements in line casting machines of the well known class employing a pair of vise jaws for presenting lines of character bearing matrices to a mold for casting type bars or slugs therefrom, an example of a machine of that class being disclosed in U. S. Letters Patent No. 436,532 granted September 16, 1890 to O. Mergenthaler.

It has been proposed to provide one of the vise jaws of such machines, on the side of such jaw next to the mold, with a mark such as an aperture or cavity which, during casting, will produce a corresponding projection on the cast slug, which will serve as a mark or guide to indicate the point at which the slug is to be sawed off to the desired length, examples of such an arrangement and of the slug produced thereby being disclosed in U. S. Letters Patents Nos. 1,434,308 and 1,438,131 granted Oct. 31, 1922 and Dec. 5, 1922 respectively to A. H. Narrow.

It is sometimes desirable, however, especially when both vise jaws are moved toward one another for the purpose of casting slugs without type characters or of centering the type characters with respect to the length of the slugs and to avoid subsequent objections, such for example as objectionable printing from such projections which will stand at least as high as the type characters on the slugs or the necessity of re-moving such projections to render the slugs suitable for use, to omit the casting of such projections on the slugs, the omission of such projections from such slugs being possible since such slugs may be cast to the entire length and would then be suitable for use without requiring any sawing off.

To enable this result to be accomplished, the present invention provides means whereby the aperture or mark carried by the vise jaw may be rendered inoperative in any desired manner such as automatically by the movement of the vise jaws toward one another or manually.

In carrying out the invention, it is preferable to employ an aperture to serve as the mark, and when the aperture is to be rendered inoperative automatically, it is preferable to provide such aperture in the vise jaw and to provide a pin for closing it automatically by movement of the pin under the action of a spring when the respective vise jaw is removed from its usual stop, and when the aperture is to be rendered inoperative manually, it is preferable to provide the aperture in off-center position in a circular body which is rotatably mounted in the mold engaging face of the respective vise jaw so that the

aperture may be moved out of the plane of the mold cavity by rotating such body.

In the accompanying drawing:

Fig. 1 is a top plan, partly in section, of a vise jaw provided with means for automatically closing and opening a marking aperture therein, the jaw being shown in its normal position against its stop and the aperture open;

Fig. 2 is a top plan of a portion of the vise jaw shown in Fig. 1 but showing the marking aperture closed;

Fig. 3 is an elevation of the vise jaw shown in Figs. 1 and 2, indicating the position of the marking aperture with respect to the mold cavity;

Fig. 4 is a top plan, showing the invention applied to the vise of a typographical machine;

Fig. 5 is an elevation of a portion of a vise jaw provided with manual means for rendering the marking aperture operative or inoperative; and

Fig. 6 is a top plan of the vise structure shown in Fig. 5.

According to the embodiment of the invention shown in Figs. 1 to 4 inclusive, the rear or casting face of the vise jaw *a* which is preferably the left hand or adjustable jaw in the machine, has an aperture *c* therein at the height of the slug casting cavity *x* of the mold. A pin *h* fits slidably in said aperture and closes it when the vise jaw *a* is moved inwardly or toward the left from the position shown in Fig. 1. This pin *h* is located in a recess *s* in the matrix engaging face of the vise jaw *a* and is normally held in the retracted position shown in Fig. 1 by a spring *i*, the aperture *c* being then open so that the slugs will be cast with a projection corresponding to the aperture *c*. In order to push the pin *h* into the aperture *c*, a pin *k* is rotatably mounted in the vise jaw *a*, said pin having a cam head or toe *l* thereon which permits the pin *h* to recede in the aperture *c*, under the action of its spring *i*, into the position shown in Fig. 1 when said cam head or toe *l* occupies the position shown in that figure, and when said cam head or toe *l* is in the position shown in Fig. 2, it will push the pin *h* into the aperture *c* to such extent that its end lies in the plane of the mold engaging face of the vise jaw, as shown in the latter figure. The pin *k* has an actuating lever *j* fixed thereto and linked to a two-armed lever *m* one end of which is forked to receive a pin *t* on the lever *j*. The lever *m* is pivoted at *n* on the guide *o* of the vise jaw *a* and is under the control of a spring *p* the action of which tends to move said lever into the position shown in Fig. 2. A bar *q* is freely movable end-

110

wise in the guide *o*, it being held against the lever *m* by the jaw stop *r* on the machine when the vise jaw *a* is against its said stop, so that the pin *h* will then be retracted to open the aperture 5 *c*, as shown in Fig. 1, but if the vise jaw *a* is moved inwardly or toward the left in Fig. 1, away from the stop *r*, which occurs, for example, when casting slugs without type characters or slugs 10 with the type characters centered thereon, the bar *q* will release the lever *m* so that it will assume the position shown in Fig. 2 under the action of the spring *p*, and the aperture *c* will then be closed by the pin *h*.

Fig. 4 shows the vise of a line casting machine 15 having the present invention applied thereto, the vise jaw *a* cooperating with a companion vise jaw *a'* and both jaws being movable toward and from one another and adapted to receive and clamp a matrix line between them and hold the 20 matrix line in casting position in front of a mold *X* having the slug casting cavity *x* therein, the vise jaws having suitable means for moving them simultaneously and equidistantly toward one another to center matrix lines with respect to 25 the used length of the slugs, such for example as racks *u* and *v* connected to the respective jaws and meshing with an interposed pinion *w* rev- 30 olutely mounted on the vise frame. With such an arrangement, it will be understood that while the vise jaw *a* is in its retracted position against its stop *r*, the latter, pressing against the bar *q*, will rock the lever *m* and cam head *l* into the 35 positions shown in Fig. 1 and thus allow the spring *i* to hold the pin *h* in its retracted position in the aperture *c*, thereby opening the latter so that a projection will be cast on the type character bearing edge of the type slug cast in the 40 mold by metal which will enter said aperture from the mold cavity which will then be in communication with said aperture, but when the vise 45 jaw *a* moves inwardly or toward the other jaw, as when centering a matrix line as shown in Fig. 4, the bar *q* will be carried away from the jaw stop *r* and the spring *p* will then act to overcome 50 the action of the spring *i* and rock the lever *m* and cam head *l* into the positions shown in Figs. 2 and 4, thereby moving the pin *h* into the aperture sufficiently far to completely fill or close it, so that no projection will then be cast on the 55 character bearing edge of the slug. Return of the vise jaw *a* against its stop *r* will cause the latter to press against the bar *q* and said bar will act on the spring tensioned end of the lever *m* to rock it into the position shown in Fig. 1, the 60 cam head *l* then occupying a position which will allow the spring *i* to retract the pin *h* and thereby open the aperture *c*, as shown in this figure.

Figs. 5 and 6 show manually controlled means for the same purpose, according to which a circular body *b* is positioned rotatably in a circular recess in the left hand vise jaw *a'*, the face of this body lying in the same plane with the casting or mold engaging face of the vise jaw *a'*. The body *b* is provided with an aperture *c'* at a point removed from its axis of rotation, and this aperture, as shown by the full lines in Fig. 5, is at the height of the mold cavity *x* so that a projection will then be cast on the type bearing edge of the slug cast in the mold. A partial revolution of the circular body *b* will carry the aperture *c'* into the dotted-line position shown in Fig. 5, said aperture being then located below the mold cavity and hence out of communication therewith, so that a slug cast in the mold 70 while the aperture *c'* is so positioned will be

without such projection, the body *b* then presenting a smooth surface to the mold cavity at the casting level. The vice jaw *a'* is preferably provided with a recess to receive a vertically movable plunger *e* having a handle *d* at its upper end, the plunger being connected at its lower end to said rotatable body by a pin *f* which extends across a recess *g* in said body and accommodates the lower end of the plunger, the latter being depressed as shown by the full lines in Fig. 80 5 to rotate the body *b* in a direction to bring the aperture *c'* into operative position as shown by the full lines in this figure, and raised into the dotted line position to rotate the body *b* in a direction to carry said aperture into inoperative 85 position as shown by the dotted lines in said figure.

I claim as my invention:—

1. In a line casting machine having a vise for holding a matrix line against a mold for casting a slug therefrom, one of the vise jaws being solid and having a casting face integral therewith and having permanently associated therewith a mark adapted to produce a corresponding mark on the cast slug as a guide for the cutting 90 off of the slug to a desired length, means for rendering said mark on the jaw inoperative.

2. In a line casting machine having a vise for holding a matrix line against a mold for casting a slug therefrom, one of the vise jaws being solid and having a permanent casting face integral therewith and provided with a mark located thereon to communicate with the slug casting cavity of the mold for casting a corresponding cut-off indicating mark on the type 100 bearing edge of the slug, means for rendering said mark on the jaw operative or inoperative while in communication with the slug casting cavity in the mold and during the casting of a 110 slug therein.

3. In a line casting machine having a vise for holding a matrix line against a mold for casting a slug therefrom, one of the vise jaws being movable from a given position toward the other jaw and having a mark located thereon to communicate with the slug casting cavity of the mold for casting a corresponding cut-off mark on the type bearing edge of the slug, means for automatically rendering said mark on the jaw 120 inoperative to cast a corresponding mark on the 125 slug when said jaw is moved from its given position toward the other jaw.

4. In a line casting machine having a vise for holding a matrix line against a mold for casting a slug therefrom, one of the vise jaws being movable from a given position toward the other jaw and having a mark located thereon to communicate with the slug casting cavity of the mold for casting a corresponding cut-off mark on the type bearing edge of the slug, means controlled 130 according to the position occupied by said movable jaw for rendering the mark thereon operative while said jaw occupies said given position and for rendering said mark inoperative while said movable jaw is removed from said given 140 position.

5. In a line casting machine having a vise for holding a matrix line against a mold for casting a slug therefrom, one of the vise jaws being movable from a given position toward the other jaw and having a casting face integral therewith and having permanently associated therewith a mark located to communicate with the slug casting cavity of the mold for casting a corresponding cut-off mark on the type bearing 145 150

- edge of the slug, means operative manually to move said mark on the movable jaw into and out of the plane of the mold cavity and thereby render said mark either operative or inoperative, as desired.
6. In a line casting machine, in combination, a vise jaw having a casting cavity in the mold side thereof, a reciprocable filling piece operative in said cavity, and actuating means for said filling piece operative to render said cavity ineffective automatically.
7. In a line casting machine, in combination, a movable vise jaw having a casting cavity in the mold side thereof, a filling piece reciprocable in said cavity, and means responsive to the movement of said vise jaw for moving said filling piece to render said cavity operative or inoperative.
8. In a line casting machine, a vise having jaws for holding a matrix line against a mold having a slug casting cavity, one of said vise jaws having a movable body forming a portion of its casting face adjacent to the mold, said body having a casting cavity located therein, and means for moving said body to locate said cavity therein at different levels in the plane of the jaw casting face.
9. A vise jaw for line casting machines hav-
- ing associated therewith a body provided with a casting cavity and forming a portion of the casting face of the jaw, said body being movable in the jaw to locate said cavity at different levels in the plane of said casting face.
10. In a line casting machine having a vise jaw to cooperate with the slug casting mold thereof, a round body in the mold side of said jaw and bearing a mark at a distance from its central axis for producing a corresponding mark on a slug as a guide when sawing off the slug to the desired length, said body being rotatable on its said axis to move the mark thereon out of the plane of the slug casting cavity of the mold.
11. In a line casting machine, a vise jaw to cooperate with the slug casting mold thereof, the mold side of said jaw having an aperture therein to produce a corresponding mark on the slug as a guide when sawing off the slug to the desired length, a stop against which the jaw may rest and move inwardly therefrom, a movable pin for closing said aperture in the jaw, and means including a spring for actuating said pin to close said aperture automatically when the jaw is moved inwardly from said stop.
